Application May 28, 1932, Serial No. 614,117
Renewed October 22, 1936

19 Claims. (Cl. 250—36)

My invention relates to improvements in television systems embodying a cathode ray tube provided with ray-deflecting coils, or other equivalent electron device, at either or both the transmitting and receiving stations, and, more particularly, to improved apparatus for deflecting the electrons in such tubes or devices for scanning purposes.

In television systems of the general character referred to, it is important that saw-tooth current waves, at the line-scanning and framing frequencies, respectively, be caused to pass through ray-deflecting coils. For this purpose, the so-called "peak" circuit is used, which comprises a network including a resistance and a condenser, the network being connected across the input circuit of a voltage amplifier tube in the output circuit of which is connected one of the sets of deflecting coils.

In operation, there is developed across the network a voltage wave of the shape required to cause the saw-tooth current wave to pass through the inductive circuit including the deflecting coils, and this wave is made up of two components, one being a saw-tooth component which appears across the condenser in the network, the other being an impulse component which appears across the resistance in the network.

While the various systems referred to lend themselves to satisfactory operation, it is a fact that in these systems, as heretofore known, the shape of the current wave through the deflecting coils is not a perfect saw-tooth. This is attributed to any one of the following, or the joint effect thereof: the non-linear plate-current vs. grid-voltage characteristic of the voltage amplifier tube, a non-linear charge characteristic of the condenser in the network, charge current taken by the grid bias resistor of the amplifier tube which would otherwise go to the condenser, distributed capacitance across the output circuit of the amplifier tube, and inductive drop in the load circuit of this tube, which circuit includes the deflecting coils.

With the foregoing in mind, it is one of the objects of my invention to provide an improved deflecting circuit or apparatus of the character referred to which not only has the various advantages of the deflecting circuits proposed heretofore, but which, also, causes a practically perfect saw-tooth current wave to pass through the deflecting coils.

Other objects and advantages will hereinafter appear.

55 In accordance with my invention, a negative

feed-back action is utilized from a circuit of a voltage amplifier tube in the deflecting circuit to reshape the voltage wave which would otherwise appear across the input circuit of this tube, the nature and degree of the reshaping being such as to compensate for each of the various actions referred to above which cause distortion of the voltage wave shape from the exact shape required.

Further, in accordance with my invention, a network impedance is connected in one of the circuits of the voltage amplifier tube in the deflecting circuit, and this network is caused to operate to effect a feed-back action to the input circuit of this tube and of such character as to compensate for each of the various actions referred to which would otherwise distort the wave from the shape required.

My invention resides in the system and method of operation of the character hereinafter described and claimed.

For the purpose of illustrating my invention, an embodiment thereof is shown in the drawings, wherein

Figure 1 is a diagrammatic view of a television receiving system embodying my invention;

Figs. 2 and 3 are graphical views illustrative of the principle of operation in Fig. 1;

Fig. 4 shows a number of feed-back networks which might be embodied in Fig. 1, as modifications; and

Fig. 5 is a diagrammatic view of a deflection circuit proposed for embodiment in Fig. 1 as a modification.

The particular embodiment of my invention shown in Fig. 1 comprises a cathode ray tube 10 having its control-grid circuit 11 supplied with picture signals by way of a connection 12 terminating at an adjustable contact 13 associated with a resistance 14, the latter being connected across the output of a suitable radio receiver 15.

A cathode ray 16 is caused to scan a fluorescent screen 17 by electromagnetic coils 18 for deflecting the ray horizontally and by electromagnetic coils 19 for deflecting the ray vertically. For this purpose, a horizontal deflection circuit, designated generally by the reference numeral 20, generates a saw-tooth current wave at a suitable line-scanning frequency, for example 4320 cycles, for a picture having 180 lines and for 24 frames a second, and supplies this wave to the coils 18. In like manner, a vertical deflection circuit, designated generally by the reference character 21, generates a saw-tooth current wave at the pic-

55

ture-frame frequency, for example, 24 cycles, and supplies this wave to the coils 19.

The vertical deflection circuit 21 includes an oscillator circuit 22 comprising an electron tube 23 and a transformer 24 providing an inductive coupling between the plate and grid circuits. A blocking condenser 25 is connected as shown between the grid of the tube 23 and the grid winding 26 of the transformer. An adjustable resistance 27 provides a leakage path to ground for the electrical charge stored in the condenser 25, as will hereinafter more fully appear.

The manner of operation of the oscillator circuit 22 will now be explained. At the start of the operating cycle, the plate current increases, and the polarity of the grid winding 26 of the oscillation transformer is such that the grid is then driven positive. This action is effective to increase the plate current still further until a condition of saturation is reached, after which the plate current begins to decrease. From this point, the plate current decreases almost instantaneously to zero by reason of the fact that, at the instant the plate current begins to decrease, the polarity of the grid is reversed by the action of the transformer windings with respect to each other. This drives the grid almost instantaneously to a negative potential far below that necessary for cut-off.

During the action just described, the grid draws current for a very short period and a negative charge is, accordingly, stored in the condenser 25. The charge stored by the condenser is not appreciably affected by the resistance 27 because the latter is relatively high compared to the resistance between the grid and cathode. The negative charge stored in the condenser blocks the tube against further oscillation, because this charge places on the grid a negative potential much greater than that required for cut-off. This negative charge, therefore, must be reduced by leakage through the resistance 27 before the plate can again begin to draw current to start the next cycle of operation. The time required for this discharge is determined by the ratio existing between the value of the resistance 27 and the capacity of the condenser 25. This ratio is made such that at the end of the complete operating period, which equals a picture-frame period, the charge will not have leaked off sufficiently to reduce the negative bias quite to a potential such that the plate can again begin to draw current. At this instant, however, a sharp framing impulse is received and this is effective to counteract the bias potential on the grid of the tube 23 sufficiently to permit space current to flow, thus initiating the next succeeding operating cycle.

By exciting the grid circuit from the plate circuit, and by using the proper values of resistance and capacity, the oscillator circuit is permitted to make only one oscillation during each complete operating period. Only a single, sharp impulse of current, therefore, passes through the plate circuit during each complete operating cycle, and this impulse, under the control of the received framing impulse, always occurs exactly at the same point in each complete operating period. In the particular embodiment shown, the capacity of the blocking condenser 25 and the value of the associated resistance 27 are such that the period during which the plate of the tube 23 draws current is about one-fiftieth of the entire operating period of the oscillator circuit.

The current impulses developed in the plate circuit of the tube 23, as just explained, cause a

saw-tooth voltage wave to appear across a condenser 28 and an impulse voltage wave to appear across a resistance 29, the condenser 28 and the resistance 29 being connected in series relation with respect to each other and comprising a network 30 connected in the plate or output circuit of the tube 23. A voltage wave 31 comprised of the saw-tooth and impulse components, therefore, appears across the network 30. The saw-tooth voltage wave appearing across the condenser 28 is attributed to the fact that the condenser is charged through a relatively higher resistance 32 connected to the potential supply source shown, and to the fact that when the charge reaches a definite level, it is discharged practically instantaneously by the sharp impulse of current which then passes through the tube 23.

Neglecting distorting actions which, however, are always present, the voltage wave 31 would be effective, when applied to the input circuit of a voltage amplifier tube 32, to cause a perfect saw-tooth current wave 33 to pass through the inductive circuit including the electromagnetic deflecting coils 19. However, on account of the distortion actions, the plate current curve appears as though the shape of the voltage wave across the resistor 34 is more like the letter S, as represented by the voltage wave 35. The reason for this is that the upper end portion A of the wave 35 would droop, as indicated in Fig. 2, by reason of the tube plate-current characteristic, the non-linear charge characteristic of the condenser 28, and the fact that an appreciable amount of current, which would otherwise go to charge the condenser 28, passes through the resistor 34.

The lower end portion B of the wave 35 would also be rounded or drooped away from the desired perfect saw-tooth shape by reason of the distributed capacitance across the output circuit of the tube 32, the inductive drop in the load circuit of this tube, and the plate current characteristic of this tube.

For the purpose of compensating for the influences referred to which distort the voltage wave 35 to the S-shape of the wave 35, I propose to connect an impedance network, designated generally by the reference numeral 36, in the cathode circuit of the tube 32, as shown. The values of resistance, inductance and capacity in this network are so chosen that the voltage wave 37 which appears across the same is generally S-shape, but the end portions thereof are of greater curvature, or droop more than the end portions A and B of the wave 35. The network 36 effects a negative feed-back action through the cathode of the tube 32, so that the voltage wave 38, which appears between the grid and cathode of the tube 32, is graphically the difference between the waves 35 and 37. The wave 38 is also S-shape, as indicated, but the end portions thereof are distorted or bent in the opposite directions to the end portions of the waves 35 and 37. This is due to the fact that the end portions of the wave 37 are more sharply bent or rounded than the end portions of the wave 35, as explained.

The shape of the current wave in the load circuit of the tube 32 will be distorted from the shape of the wave 38, on account of the plate-current characteristic of the tube 32, the distributed capacitance across the load circuit of this tube, and the inductive drop in this load circuit. The shape of the voltage wave 38, as determined by the nature of the network 36, is such, however, that the distortion is just sufficient to straighten out the curved ends of the

wave 38, whereupon a practically perfect saw-tooth current wave is caused to flow through the load circuit including the coils 19. In other words, the voltage wave 38 is distorted in anticipation of other distorting actions further on in the circuit, and in such manner that the latter distorting actions compensate for the previous distortion to obtain the perfect saw-tooth current wave desired.

10 The saw-tooth current wave 33 occurs at a frequency of 24 cycles, as determined by the received framing impulses occurring at the rate of 24 a second and which are applied to the grid circuit of the tube 23 by the connection 39.

15 The horizontal deflection circuit 20 is connected and operates in the same manner as the vertical deflection circuit 21, the various values of resistance, inductance and capacity being so chosen, however, that a saw-tooth current wave 20 40 is caused to flow through the coils 18 at a frequency of 4320 cycles. This frequency is maintained by the received synchronizing impulses occurring at the rate of 4320 a second and which are applied to the circuit 20 by a connection 41. The two frequencies given, for example, provide for 24 picture frames a second, each having 180 lines.

25 In describing the manner of operation of the embodiment of my invention disclosed in Fig. 1, it has been assumed, for example, that the picture signals and the synchronizing impulses are being transmitted in the same channel, with the impulses at a substantially greater amplitude than the picture signals. Both the horizontal 30 and vertical impulses are transmitted at the same amplitude, but are of different shapes so that these impulses have substantially different steepness of wave fronts. The horizontal impulses are transmitted at the end of each picture line, and occur at the rate of 4320 a second, while the vertical impulses are transmitted at the 35 end of each frame and occur at the rate of 24 a second.

40 At the receiving station, the picture signals and the synchronizing impulses appear across the resistance 14 in the form of a single wave. This wave is supplied to the input circuit of a suitable filter apparatus 43 which blocks the picture signals but passes the synchronizing impulses which 45 are of substantially greater amplitude than the latter, as explained. The apparatus 43 is effective to distinguish between the horizontal and vertical impulses, and passes the former to the horizontal deflection circuit 20 by way of the connection 41, and passes the latter to the vertical deflection circuit 21 by way of the connection 39.

45 With reference, more particularly, to Fig. 3, the reverse curvature of the right-hand end portion of the wave 38 is attributed to the inductance shunt 44 in the network 36, and the reverse curvature of the left-hand portion of this wave is attributed to the capacitance shunt 45 in the network. This effect of the inductance shunt 44 becomes more pronounced if the design is such 50 that the magnetic core more nearly approaches saturation as the current through it reaches the peak value. Both end portions, or only one end portion, of this wave may be reversed, or the existing curvature may be made more nearly straight, as might be required. Other networks for this purpose may be used, such as are shown in Fig. 4. In Fig. 4, the networks in the upper row and the first network in the lower row include 55 an inductance shunt and a capacitance

shunt, and each would therefore be effective to reverse the curvature of both end portions of the wave. The second and third networks in the lower row include only an inductance shunt, and would be effective to reverse the curvature of only the right-hand end portion of the wave 38. The fourth and fifth networks in the lower row include only a capacitance shunt, and would be effective to reverse only the left-hand end portion of the wave 38.

10 In Fig. 5 is shown a vertical deflection circuit which may be substituted for the circuit 21 in Fig. 1. In this circuit, an oscillator circuit 46 is used, comprising the tube 47 which operates to discharge a condenser 48, the latter being charged through a resistance 49 from the source of supply shown. The oscillator 46 is self-oscillating on account of a feed-back connection 50, through a condenser 51, from the output circuit of a voltage amplifier tube 52 to the input circuit of the tube 47. The adjustments are such that the oscillator 46 is self-oscillating at a frequency slightly below the required framing frequency, which in this case would be 24 cycles, the received framing impulses applied to the input circuit of the tube 47 by the connections 53 and 54 operating to drive the oscillator and maintain the same at exactly an operating frequency of 24 cycles. The framing impulses are applied to the connections 53 and 54 if they are positive. If these impulses are negative, they are applied to the connections 55 and 56.

15 A network 56, corresponding to the network 36 in Fig. 1, is connected as shown in the load circuit of the output tube 52, and a connection 57 leads therefrom to a resistance 58 connected to the grid of the tube 52.

20 In operation, a voltage wave 59, corresponding to the wave 37 in Fig. 1, appears between point P and ground. A voltage wave 60, corresponding to the wave 35 in Fig. 1, appears across the condenser 48. The wave 59 is in the nature of a negative feed-back to the input circuit of the tube 52, and is subtracted from the wave 60 to develop the reverse voltage wave 61, corresponding to the wave 38 in Fig. 1. The reverse distortion of the wave 61 is just sufficient to compensate for the distorting effects caused by the plate-current characteristic of the tube 52, the distributed capacitance across the output circuit of this 25 tube, and the inductive drop in the load circuit of this tube. The result is that when the voltage wave 61 is applied to the input circuit of the tube 52, a practically perfect saw-tooth current wave 30 is caused to pass through the coils 19.

35 The impedance of the network 56 is relatively low as compared with that of the tube 52, so that it does not directly or appreciably affect the current in the load circuit while supplying the negative feed-back voltage to the grid circuit.

40 Since the voltage waves shown are not accurately to scale, they do not show that a definite loss of exciting voltage available for the amplifier grid is caused by the negative feed-back. Though this loss is not desirable, it is not serious, 45 as in actual practice the available signal is more than ample to make up for the loss.

45 The various values of resistance, capacity, inductance and voltage designated in the drawings have been found to provide for very satisfactory 50 operation. However, these values are not critical in any strict sense of the word, and may be varied over a substantial range. Electrostatic deflection may be used in lieu of electromagnetic deflection. Furthermore, in this connection, va- 55

rious other changes might be made, such as in the circuit arrangement, without departing from the spirit of the invention or the scope of the claims.

5. I claim as my invention:

1. In the art of electronics wherein it is required that a substantially saw-tooth current wave pass at a given frequency through an inductive circuit comprising the load on an electron tube, the method of operation which comprises developing across the input circuit of said tube a voltage wave of a given shape and at said frequency, utilizing a feed-back action from a circuit of said tube to reshape the voltage wave, the reshaped wave being such that it is effective to cause a substantially saw-tooth wave to pass through the inductive circuit, and utilizing the reshaped voltage wave to cause the saw-tooth current wave to pass through the inductive circuit at said frequency.

2. In a circuit for deflecting an electron beam along a substantially saw-tooth path, an electron tube in the output circuit of which a substantially saw-tooth electrical wave appears at a given frequency, an electrical network connected in a circuit of said tube and operating to effect a feed-back action to the input circuit of said tube of such character as to reshape, at said frequency, the voltage wave which would otherwise appear across said input circuit, the reshaped wave being such that it is effective to cause a substantially saw-tooth electrical wave to appear in said output circuit, and a second tube forming part of said deflecting circuit for causing said deflecting circuit to oscillate.

3. In a circuit for deflecting an electron beam along a substantially saw-tooth path, an electron tube in the output circuit of which a substantially saw-tooth electrical wave appears at a given frequency, an impedance network connected in the common grid cathode-plate cathode circuit of said tube and operating to effect a feed-back action to the input circuit of said tube of such character as to reshape, at said frequency, the voltage wave which would otherwise appear across said input circuit, the reshaped wave being such that it is effective to cause a substantially saw-tooth electrical wave to appear in said output circuit, and a second tube forming part of said deflecting circuit for causing said deflecting circuit to oscillate.

4. In a circuit for deflecting an electron beam along a substantially saw-tooth path, an electron tube in the output circuit of which a substantially saw-tooth electrical wave appears at a given frequency, an impedance network connected in the output circuit of said tube and operating to effect a feed-back action to the input circuit of said tube of such character as to reshape, at said frequency, the voltage wave which would otherwise appear across said input circuit, the reshaped wave being such that it is effective to cause a substantially saw-tooth electrical wave to appear in said output circuit, and a second tube forming part of said deflecting circuit for causing said deflecting circuit to oscillate.

5. In a circuit for causing a substantially saw-tooth current wave to pass through ray-deflecting coils, an electron tube at the output end of the deflection circuit, a relaxation oscillator circuit connected to the input circuit of said tube, and an impedance network connected in one of the circuits of said tube and operating to effect a feed-back action to the input circuit of said tube of such character as to reshape the voltage wave

which would otherwise appear across said input circuit, the reshaped wave being such that it is effective to cause a substantially saw-tooth current wave to pass through the load circuit of said tube.

6. In the art of electronics wherein it is required that a substantially saw-tooth electrical wave be caused to appear in an electrical circuit, the method of operation for such purpose which comprises developing electrical waves each at the same frequency and of generally similar shapes but of different curvatures, deriving from said waves another electrical wave of such shape that it is effective to cause a substantially saw-tooth wave to flow through said circuit, and utilizing such derived wave to cause the required saw-tooth wave to flow through said circuit.

7. In a circuit for deflecting an electron beam along a substantially saw-tooth path, an electron tube in the output circuit of which a substantially saw-tooth electrical wave appears, and an impedance network connected to the common grid-cathode, plate-cathode circuit of said tube and operating to effect a feed-back action through said cathode to the input circuit of said tube of such character as to reshape the voltage wave which would otherwise appear across said input circuit, said impedance network comprising a resistance and an inductive shunt across at least a part of said resistance.

8. In a circuit for deflecting an electron beam along a substantially saw-tooth path, an electron tube in the output circuit of which a substantially saw-tooth electrical wave appears, and an impedance network connected to the common grid-cathode, plate-cathode circuit of said tube and operating to effect a feed-back action through said cathode to the input circuit of said tube of such character as to reshape the voltage wave which would otherwise appear across said input circuit, said impedance network comprising a resistor and a capacitive shunt across at least a part of said resistance.

9. In a circuit for deflecting an electron beam along a substantially saw-tooth path, an electron tube in the output circuit of which a substantially saw-tooth electrical wave appears, and an impedance network connected to the common grid-cathode, plate-cathode circuit of said tube and operating to effect a feed-back action through said cathode to the input circuit of said tube of such character as to reshape the voltage wave which would otherwise appear across said input circuit, said impedance network comprising a resistor, an inductive shunt across at least a part of said resistor, and a capacitive shunt across at least a part of said resistor.

10. In a circuit for deflecting an electron beam along a substantially saw-tooth path, an electron tube in the output circuit of which a substantially saw-tooth electrical wave appears, and an impedance network connected to the common grid-cathode, plate-cathode circuit of said tube and operating to effect a feed-back action through said cathode to the input circuit of said tube of such character as to reshape the voltage wave which would otherwise appear across said input circuit, said impedance network comprising a resistor, an inductive shunt across a part of said resistor, and a capacitive shunt across another part of said resistor.

11. In combination, means for generating a voltage wave having a saw-tooth wave form, each saw-tooth consisting of a portion of gradually changing amplitude in one direction which occurs

6 during a useful deflecting period and a portion of rapidly changing amplitude in the opposite direction which occurs during a return line period, a wave-utilization network coupled to said wave generating means, and means for introducing distortion in said first portion of each saw-tooth to compensate for distortion unavoidably caused in said network.

10 12. In combination, means for producing a saw-tooth voltage wave having a steeply sloping portion and a more gradually sloping portion and comprising sine wave frequency components covering a wide frequency range, a wave-utilization network, means for coupling said wave producing means and said network, said network having the characteristic that it causes the more gradually sloping portion of a saw-tooth wave to bend over, and means for so accentuating the low frequency components of said voltage wave as compared 20 with its higher frequency components that said bending over is compensated.

13. In combination, a vacuum tube having an input circuit and an inductive output circuit, means for generating a voltage wave having a saw-tooth wave form and comprising sine wave frequency components covering a wide frequency range, means for impressing said wave upon said input circuit, and means for so preferentially acting upon the low frequency components of 30 said wave as compared with its higher frequency components that an electrical wave of substantially perfect wave form appears in said output circuit.

14. In combination, means for producing a saw-tooth voltage wave having a steeply sloping portion and a more gradually sloping portion, a wave-utilization network, means for coupling said wave producing means and said network, said network having the characteristic that it causes the more gradually sloping portion of a saw-tooth wave to bend over, and means for causing that portion of said saw-tooth voltage wave which corresponds to the bent over portion of the saw-tooth wave in said network to bend up before it is impressed upon said network at least enough to compensate for said bending over.

15. In combination, means for producing a voltage wave having a saw-tooth component which has a steeply sloping portion and a more gradually sloping portion, a wave-utilization network, means for coupling said wave producing means and said network, said network having the characteristic that it causes the more gradually sloping portion of a saw-tooth wave to bend over, and means for causing that portion of said saw-tooth component which corresponds to the bent over portion of the saw-tooth wave in said network to bend up before it is impressed upon said network at least enough to compensate for said bending over.

16. In combination, means for generating a

voltage wave having a saw-tooth component, each saw-tooth of said component consisting of a portion of gradually changing amplitude in one direction which occurs during a useful deflecting period and a portion of rapidly changing amplitude in the opposite direction which occurs during the return line period, said voltage wave having the undesired characteristic that said first portion contains an undesired distortion, a wave utilization device coupled to said wave generating means, and means for introducing distortion in said first portion to compensate for said undesired distortion.

17. In combination, means for generating a voltage wave having approximately a saw-tooth shape, said saw-tooth consisting of a portion of gradually changing amplitude in one direction which occurs during a useful deflecting period and a portion of rapidly changing amplitude in the opposite direction which occurs during the return line period, said saw-tooth wave having the undesired characteristic that said first portion contains an undesired curvature, a wave utilization device coupled to said wave generating means, and means for introducing a correcting curvature in said first portion to compensate for said undesired curvature.

18. In combination, means for generating a voltage wave having approximately a saw-tooth shape, said saw-tooth consisting of a portion of gradually changing amplitude in one direction which occurs during a useful deflecting period and a portion of rapidly changing amplitude in the opposite direction which occurs during the return line period, said saw-tooth wave having the undesired characteristic that said first portion contains an undesired curvature, an output tube having an input circuit and an output circuit, a wave utilization device coupled to said output circuit, said input circuit being coupled to said wave generating means, and means for introducing a correcting curvature in said first portion at said input circuit to compensate for said undesired curvature.

19. In combination, a vacuum tube having an input circuit and an inductive output circuit, means for generating a voltage wave having a saw-tooth wave form, said saw-tooth having a gradually sloping portion of gradually changing amplitude and a portion of rapidly changing amplitude and comprising sine wave frequency components covering a wide frequency range, means for impressing said saw-tooth voltage wave upon said input circuit, said inductive output circuit having the characteristic that it causes the said gradually sloping portion of a saw-tooth wave to bend over, and means for causing that portion of said saw-tooth wave which corresponds to the bent over portion of the saw-tooth wave in said output circuit to bend up at said input circuit to compensate for said bending over.

ALDA V. BEDFORD.
